UNITED STATES PATENT OFFICE.

HENRY K. SANDELL, OF CHICAGO, ILLINOIS, ASSIGNOR TO H. S. MILLS, OF CHICAGO, ILLINOIS.

PHONOGRAPH DRIVE MECHANISM.

1,417,109.

Specification of Letters Patent. Patented May 23, 1922.

Application filed April 11, 1921. Serial No. 460,229.

To all whom it may concern:

Be it known that I, HENRY K. SANDELL, a citizen of the United States, residing at 221 South Green Street, Chicago, in the 5 county of Cook and State of Illinois, have invented a new and useful Improvement in Phonograph Drive Mechanism, of which the following is a specification.

The present invention relates to phonographs, particularly of the disc type and to 10 dynamo-electric drive mechanism suitable for use in connection therewith. It will be fully understood from the following description thereof, illustrated by the accompanying drawings, in which:

Fig. 1 is a vertical sectional view through the disc supporting table and the drive motor thereof, taken on the broken line 1—1 of Fig. 6;

20 Fig. 2 is a horizontal sectional view on the broken line 2—2 of Fig. 1;

Fig. 3 is a detail sectional view of the governor balance wheel and the associated devices;

25 Fig. 4 is a vertical sectional detail view on the line 4 of Fig. 2;

Fig. 5 is a broken sectional detail view on the line 5 of Fig. 2;

30 Fig. 6 is a plan view of the device with the disc supporting table and the cabinet top removed;

Fig. 7 is a detail broken elevation of the laminated armature secured to the disc supporting table, and

35 Fig. 8 is a detail plan view of a portion of a lamination of said armature.

Referring more particularly to the drawings, the numeral 10 indicates the top of a cabinet, to which the drive-motor and disc

40 support are secured. A number of inverted posts 11 are secured to and depended from the cabinet top 10. To these posts is secured an annular frame 12 which may suitably be formed as a single casting, this

45 frame encircling the opening in the cabinet top 10 through which the phonograph disc supporting table passes. The frame 12 is provided with a circular portion 12^a and a segmental enlarged portion 12^b.

50 The circular portion 12^a is approximately half a complete circle and is provided with inwardly-extending pole pieces 13 at spaced intervals. Of the pole pieces 13 alternate ones are wound with coils 14. To the por-

tion 12^b of the frame or casting is secured 55 a segmental stator member 15 provided with inwardly-projecting teeth 16. The stator section 15 is preferably formed of laminations, as shown more clearly in Fig. 1 of the drawing. The stator member 15 is provided 60 with two groups of windings. One of these groups, indicated by the numeral 17, is wound in the grooves formed between the teeth 16 of the stator member 15 transversely around the latter and are arranged 65 in three sets, as more clearly shown in the diagrammatic view of the windings in Fig. 9. These windings are in series, the successive windings being reversed with respect to each other. The windings of the second 70 group indicated by 17^a, of which there are likewise three sets, are concentric and extend around the teeth 16. These windings are in series with each other, successive windings being reversed with respect to 75 each other. The transverse windings and the concentric windings are in parallel.

A transverse supporting bar or bridge 18 for the rotor parts of the device is provided at its ends with upwardly curved portions 80 terminating in the plates 19 by which it is secured to the cabinet top 10. A hollow boss 20 is rigidly secured to the cross bar 18 and extends upwardly therefrom.

Within the boss 20 is a vertical shaft 21, 85 the lower end of which enters a bearing opening 22 in the bridge 18. The shaft 21 is centered in the boss 20 by the thrust bearing 23 mounted on the boss 20 and serving also as a journal for the shaft 21. The disc 90 supporting table 24 is supported upon the shaft 22 and is provided with a depending boss 25 through which the shaft 21 passes. A number of depending posts 26 are secured to the under-side of the table 24 and to these are secured an annular rotor member 27 formed of laminations 28 and likewise a ring 29 from which radial webs 30 extend to and are secured to the boss 25 depending from the table 24. The laminations of the rotor member 27, as shown more clearly in Fig. 8, are provided with slots 31, certain of which at regularly spaced intervals are enlarged for the reception of coils, and are shown at 32. When the laminations 100 28 are assembled to form the rotor, a copper grid or squirrel cage 33 is fitted into the slots 31, as shown in elevation in Fig. 7.

Coils 34 are wound in the enlarged slots 32 prior to the placing of the squirrel cage on the rotor.

The ring 29 is formed with the depending 5 posts 35, to which is secured a sinusoidal cam ring 36. The cam ring 36 is provided with the lugs 37 which are secured to the posts 35 between felt washers 38 by means of cap screws 39. This ring forms part of the 10 governor mechanism, which is very similar to that described in my prior Patent No. 1,329,800, of February 3, 1920. The associated elements of the governor mechanism are as follows:

15 A depending bracket 40 secured to the frame 12 carries at its lower end a horizontal stationary shaft 41. Upon this is journaled a light-weight disc 42 by means of a hub 43 and a bushing 44. The disc 42 may 20 suitably be of felt, aluminum or the like. Beyond the disc 42 is independently journaled a sleeve 45, the end of which is formed as a fork 46 which straddles the edge of the cam ring 36. At its ends the fork 46 carries 25 two relatively transverse plates or springs 47 and 48, upon each of which is mounted a felt contact or friction block 49 and a metal contact block 50. The distance between the contact blocks 49 and 50 on each of the plates 30 is half the length of one of the waves of the cam 36, and they are so arranged that the felt friction block on either of the plates faces the metal contact block on the other. The distance between the opposing contact 35 blocks on the two plates is slightly greater than the thickness of the plates 36, for the purpose hereinafter set forth. The sleeve 45 of the fork 46 is connected to the balance wheel 42 by means of a spiral spring 51, the 40 inner end of which is secured to the sleeve 45 and the outer end to the balance wheel 42. One end of a light tension spring 52 is secured to the balance wheel 42 at a point in horizontal alignment with its axis of rotation, the other end of this spring being secured to one end of lever 53, the other end of which is pivoted to a plate 54 secured to a support 55. The tension upon the spring 52 may be varied by rotating a spiral cam 45 56 by means of a knob or button 57 above the cabinet top 10, the cam engaging the lever 53. The operation of this governor mechanism has been fully set forth in my prior patent above referred to.

55 The relation of the various windings of the devices to each other is shown in Fig. 9. The windings 34 in the rotor are in series with each other. At one end they are grounded by means of the terminal wire 58. 60 At the other end they are connected by the wire 59 to the governor cam wheel 36. The fork 46 carrying the plates 47 and 48 and the metal contact members 50 is connected by a wire or conductor 60 to the switch contact 65 61. The field coils 14 are in series with each

other and at one end are connected to the conductor 60 by means of the conductor 62 and at the other end are connected by conductor 63 to the conductor 64, to which a main line bringing in current 65 is likewise 70 connected. Switch terminal 66 is grounded. Switch terminal 67 is connected to the terminal 68, to which the second main line 69 is likewise connected. Switch terminal 70 is connected by conductor 71 to the coils 17, 75 which are likewise connected at their other ends with the main line 65. Switch terminal 72 is connected through the windings 17^a by conductor 73 and these windings are in turn connected to the conductor 64. 80

Fig. 9 shows the windings with the switch 75 in position for use of the device with a direct current. Assuming that the line 69 is positive and the line 65 negative, the flow of the current is through line 69 to switch pole 68, then to switch terminal 67 from which it passes through the switch to terminal 66 and from there to the ground. It passes through the ground connection to the conductor 58, from which it passes through the 90 series of windings 34 of the rotor and to the cam ring 36. From the cam ring 36 it passes at the moments of contact with the metal contact blocks 50 to the conductor 60, from which it travels through two paths in 95 parallel. One of these is to switch terminal 61, switch terminal 70, conductor 71, and coils 17 to main line 65. The other is through conductor 62, coils 14 and conductors 63 and 64 to the main line 65. In the 100 position shown in this figure, the metal contact blocks 50 are in contact with the cam ring 36, but are just about to break contact. As the upper and lower contact blocks 50 pass over the crest of the waves of the cam 105 ring 36, they break contact, the felt or insulating contact blocks 49 then being in contact with the ring. The felt contact blocks 49 in turn break contact and the metal contact blocks 50 again make contact when the 110 crest of the next wave is reached. There is thus one contact period between the metal blocks 50 and the cam ring 36 for each complete wave on the ring. The number of coils 34 are so disposed with reference to the field 115 coils 14 and 17 that contact is made and current passes through the coils as coils 34 approach the poles formed by the coils 14 and 17, and the contact is broken at the ring when the coils 34 are opposite the poles 120 formed by the coils 14 and 17. The current passing through the coils 34, 14 and 17 is hence a pulsating direct current. If desired, the coils 14 may be omitted, the coils 17 alone being sufficient for the field for D. C. 125 operation. The direct current motor thus formed is, as is readily apparent, not a self starting motor, inasmuch as there are certain positions thereof in which starting will not be effected. A slight rotation of the 130

table and of the rotor will start the motor at any time.

When the switch 75 is thrown to its reverse position, the series of coils 34 and 14 are cut out and the coils 17 and 17^a act upon the rotor provided with the squirrel cage to form an alternating current motor as set forth in my prior application Serial No. 290,705, filed April 17, 1919, which is a division of my earlier application Serial No. 226,804, filed April 5, 1918.

I claim:

1. In a dynamo-electric drive for phonographs, a rotor secured to the phonograph table, said rotor comprising a magnetic ring, and a plurality of series connected windings at spaced angular intervals around the ring, a stator having a plurality of angularly spaced series connected pole windings and means for passing intermittent direct current impulses simultaneously through the stator and rotor windings, said means comprising a contact ring having a sine-wave contour, an oscillatable fork straddling the ring, said fork having on each side of the ring a contact member and a friction member spaced apart one-half of a wave of the ring, the contact member on each side facing the friction member on the other and being spaced therefrom somewhat more than the thickness of the ring whereby the contact members make contact with the ring simultaneously over one-half of each wave of the ring.

2. In a dynamo-electric drive for phonographs, a rotor secured to the phonograph table, said rotor comprising a magnetic ring, and a plurality of series connected windings at spaced angular intervals around the ring, a stator having a plurality of angularly spaced series connected pole windings and means for passing intermittent direct current impulses simultaneously through the stator and rotor windings, said means comprising a contact ring having a sine-wave contour, an oscillatable fork straddling the ring, said fork having on each side of the ring a contact member and a friction member spaced apart one-half of a wave of the ring, the contact member on each side facing the friction member on the other and being spaced therefrom somewhat more than the thickness of the ring whereby the contact members make contact with the ring simultaneously over one-half of each wave of the ring, and means for varying the periodicity of oscillation of the fork whereby it acts to govern the rate of travel of the ring by its braking effect thereon.

3. A circuit control device comprising a contact ring having a sine-wave contour, a relatively stationary fork straddling said ring and having a contact member on each side thereof, said contact members being spaced apart somewhat more than the thick-

ness of the ring, and means for rotating the ring.

4. A circuit control device comprising a contact ring having a sine-wave contour, an oscillatable fork straddling said ring, said fork having on each side of the ring a contact member and a friction member spaced apart one-half of a wave of the ring, the contact member on each side of the ring facing the friction member on the other and being spaced therefrom somewhat more than the thickness of the ring, and means for rotating the ring whereby the contact members make contact with the ring simultaneously over one-half of each wave of the ring.

5. A circuit control device comprising a contact ring having a sine-wave contour, an oscillatable fork straddling said ring, said fork having on each side of the ring a contact member and a friction member spaced apart one-half of a wave of the ring, the contact member on each side of the ring facing the friction member on the other and being spaced therefrom somewhat more than the thickness of the ring, and means for rotating the ring whereby the contact members make contact with the ring simultaneously over one-half of each wave of the ring, and means for varying the periodicity of oscillation of the fork whereby it acts to govern the rate of travel of the ring by its braking effect thereon.

6. In a dynamo electric drive for phonographs, a rotor secured to the phonograph table, said rotor comprising a magnetic ring, a copper grid embracing the ring and a plurality of coils at spaced angular intervals around the ring to form poles when energized, a first stator segment provided with spaced coils to form poles when energized, a second stator segment provided with spaced coils for producing a rotating field when energized by an alternating current, a contact ring having a sine-wave contour secured to the phonograph table, an oscillatable fork straddling said ring, the fork having on each side of the ring a contact member and a friction member spaced apart one-half of a wave length of the ring, the contact member on each side facing the friction member on the other and being spaced therefrom somewhat more than the thickness of the ring, whereby the contact members make contact with the ring simultaneously over one-half of each wave of the ring, means for varying the periodicity of oscillation of the fork whereby it acts to govern the rate of travel of the ring by its braking effect thereon, series circuit connection between the contact ring and the rotor coils and the first stator segment and means for selectively directing current from a main line through said series connected elements or through the coils of the second stator segment.

HENRY K. SANDELL.
